United States Patent Office

Des. 213,061
Patented Dec. 31, 1968

213,061

SIDE DELIVERY RAKE

Edward J. Johnston, La Grange, N. Donald Patterson,
Downers Grove, and Frank J. Macha, Jr., Chicago, Ill.,
assignors to International Harvester Company, Chicago,
Ill., a corporation of Delaware

Filed Nov. 2, 1967, Ser. No. 9,257

Term of patent 14 years

(Cl. D40—1)

FIG. 1

FIG. 2

FIG. 3

FIG. 1 is a top plan view of a side delivery rake showing our new design;

FIG. 2 is a front perspective view thereof; and
FIG. 3 is a rear view thereof.

We claim:

The ornamental design for a side delivery rake, substantially as shown.
